UNITED STATES PATENT OFFICE

2,348,029

RECLOSING CIRCUIT-INTERRUPTING
DEVICESidney R. Smith, Jr., Pittsfield, Mass., assignor to
General Electric Company, a corporation of
New York

Application April 16, 1942, Serial No. 439,162

8 Claims. (Cl. 200—126)

My invention relates to a reclosing circuit-interrupting device and more particularly to a circuit-interrupting device comprising a plurality of fuses only one of which is connected in the associated circuit at a time.

Fuse cutouts of the reclosing type in which a second fuse link is connected into the circuit a predetermined time after the first fuse link has blown are known and have been used to some extent. However, in connection with such devices, several difficulties have been encountered, among them being the replacement of the first fuse link after blowing thereof without momentary interruption of the circuit and consequent arcing. Another difficulty is in connection with providing a simple time-delay mechanism for providing the desired time delay between the blowing of one fuse and the inserting of another in the circuit, which is relatively simple and inexpensive and which is efficient and accurate in operation.

Accordingly, it is an object of my invention to provide a new and improved reclosing circuit-interrupting device which overcomes the difficulties enumerated above.

It is another object of my invention to provide a new and improved time-delay mechanism for a reclosing circuit-interrupting device.

Still another object of my invention is to provide a new and improved means for replacing the blown fuse link in a reclosing cutout without interrupting the circuit through the second fuse link until after the circuit has been completed through the replaced blown fuse link.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawing, in which Fig. 1 is a side elevation of a reclosing circuit-interrupting device embodying my invention with the cover of the time-delay device removed more clearly to illustrate the invention; Fig. 2 is a sectional view taken on line 2—2 of Fig. 1, and Fig. 3 is a front view of the lower portion of the device.

Referring now to the drawing, I have illustrated an insulator or insulating supporting member 10 which may be suitably supported from a pole or crossarm, not shown, as by a supporting strap or hanger generally indicated at 11 which is adapted substantially to surround

a central portion 12 of reduced diameter of insulator 10. A pair of spaced line terminals 13 and 14 are fixedly mounted on insulator 10 in any suitable manner and are provided with means, indicated at 15 and 16, respectively, for making electrical connections with a transmission line or the like. Electrically connected to upper line terminal 13 and supported from insulator 10 is a rigid conducting arm 17 projecting outwardly from terminal 13. Supported at the extreme outer end of conducting arm 17 is a double contact clip or jaw member 18 having rearwardly extending spring-biased jaw portions 19 which provide gripping means or fuse link receiving means for fuse links hereinafter described. It should be understood that, where the reclosing circuit-interrupting device uses only two fuses or, in other words, is capable of reclosing the circuit once, a single conducting arm 17 may be provided and two fuse links inserted in fuse-link contact clip or jaw member 18. It should also be understood, however, that a separate supporting arm 17 might be provided for each fuse link. Although I have disclosed 25 conducting member 17 as preferably comprising a relatively rigid arm, this might also comprise a somewhat resilient arm.

Lower line terminal 14 may be supported from insulator 10 in any suitable manner as by cementing or the like or, as illustrated in Fig. 1, by a strap 20 surrounding a reduced portion 21 at the lower end of insulator 10. Strap 20, preferably constructed of conducting material, is electrically connected to a rigid conducting 30 arm 22 connected to a U-shaped member 22' fixedly attached to a rotatable shaft 23 to permit pivotal movement of arm 22. Arm 22 is biased in a clockwise direction as viewed in Fig. 1 by spring means 24. Supported at the extreme outer end of lower conducting arm 22 is a contact clip or jaw member 25 substantially identical with jaw member 18 and comprises rearwardly extending spring-biased jaw portions 26, which provide fuse link receiving means for 35 gripping a fuse link to be described hereinafter.

A first fuse link, generally indicated at 27 comprises a pair of flexible cables 28 spaced apart at their inner ends which are interconnected by a fusible element, not shown, enclosed within a tube 29, preferably formed of horn fiber or other material that is characterized by the ability to give off a gas in the presence of the heat of an electric arc, which gas tends to extinguish said electric arc. At the outer ends 40 of the cables 28 of fuse link 27 are provided

fuse link terminals comprising loops 30 and stop members 31. The loops 30 are provided so that the fuse link 27 may readily be handled by means of a switch stick. The lower cable portion 28 of fuse link 27 is first inserted into one of the gripping portions 26 of jaw member 25 and thereafter, by means of a switch stick inserted in the upper fuse link loop 30, lower conducting arm 22 is rotated against the force of spring means 24 until upper stop member 31 is above jaw portion 19 of upper contact clip or jaw member 18. The upper cable portion 28 is then inserted so that one of the spring-biased jaw portions 19 firmly grips it and stop member 31 prevents it from slipping through jaw portions 19. The fuse link 27 is thus held under tension and is connected in the circuit between spaced line terminals 13 and 14. It should be understood that the expression "first fuse link" used in this specification and the claims herein-after refers to any fuse link inserted between conducting arms 17 and 22 whether it be the fuse link originally provided or a subsequent replacement fuse link.

In order that a second fuse link may be connected into the circuit upon blowing of first fuse link 27, insulator 10 is provided with a third terminal 32 which is adjacent to terminal 14 but spaced sufficiently therefrom for satisfactory insulating purposes under all voltage conditions normally encountered. Pivotaly connected to third terminal 32 is a conducting arm 33 having at the extreme outer end thereof a contact clip or jaw member 34 identical with jaw members 18 and 25 comprising rearwardly extending spring-biased jaw portions or gripping members 35 which provide gripping portions for receiving a fuse link therebetween. Conducting arm 33 is provided with suitable spring-biasing means, not shown, causing member 33 to rotate in a clockwise direction as viewed in Fig. 1, thereby providing tension on a second fuse link generally indicated at 36 inserted between the jaw portions provided on conducting arms 17 and 33. Second fuse link 36 is identical with first fuse link 27 and the corresponding parts thereof are designated by the same reference numerals as are the corresponding parts of first fuse link 27. Since the third terminal 32 is normally insulated from line terminal 14, fuse link 36, is not connected between line terminals 13 and 14 when fuse link 27 is in the unblown condition. Although the upper terminals of fuse links 27 and 36 are both connected between the gripping portions of contact clip or jaw member 18, it should be understood that a second conducting arm similar to 17 might be provided for fuse link 36 as was mentioned above.

In order to connect second fuse link 36 into the circuit between line terminals 13 and 14 upon blowing of fuse link 27, rigid conducting arm 22 under the force of spring means 24 is adapted to rotate with shaft 23 rapidly separating the remaining portions of fuse link 27 and, consequently, rapidly extinguishing the arc formed. At the extreme downward movement of conducting arm 22, it is adapted to be electrically connected with a switching member 37 pivotally supported at 38 by third terminal 32. A suitable stop member 39 is provided on third terminal 32 to limit the clockwise rotation of switching member 37. The extreme outer end of switching member 37 is provided with contact prongs or diverging portions 40 between which conducting arm 22 moves under the force of

spring means 24 upon rupture of first fuse link 27 and the electrical circuit between arm 22 and switching member 37 is completed. The electrical circuit from lower line terminal 14 to the lower terminal of fuse link 36 is completed through conducting strap 20, conducting arm 22, pivotally mounted switching member 37, third terminal 32, and conducting arm 33.

By means of the pivotally mounted switching member 37, it is possible to replace the first fuse link 27 upon blowing thereof without any momentary arcing of the contracts or interruption of the circuit through second fuse link 36 since, during the refusing operation, pivotally mounted switching member 37 follows conducting arm 22 and remains in electrical contact therewith after first fuse link 27 has been inserted as indicated by the dotted position shown in Fig. 1. After first fuse link 27 has been replaced, pivotally mounted switching arm 37 is moved back to the full-line position indicated in Fig. 1 by inserting a switch stick into ring 41 attached to switching member 37 as by clamp 42 and pulling downward on ring 41. Thus, the circuit through second fuse link 36 is not broken until the first fuse link 27 has been replaced and consequently no arcing occurs.

Since spring means 24 moves conducting arm 22 at high speed, it might be possible to reclose the circuit through second fuse link 36 before a temporary fault is cleared by first fuse link 27 and, accordingly, time-delay means are usually provided so that the circuit between line terminals 13 and 14 is reclosed only after a predetermined time has elapsed. However, in order to provide satisfactory operation, it is desirable that conducting arm 22 upon blowing of first fuse link 27 initially moves at high speed without any time delay to insure high-speed separation of the terminals of first fuse link 27. Also prior to electrical engagement between switching member 37 and arm 22, it is desirable that arm 22 again move at high speed to insure firm engagement between these two conducting members. To this end I provide the time-delay mechanism generally indicated at 43 which provides a simple and compact means by which conducting arm 22 is caused to move first at high speed, then is retarded sufficiently to give the desired time delay, and, subsequently, is again permitted to move at high speed. The time-delay mechanism generally indicated at 43 comprises a casing 44 within which is mounted an escapement mechanism comprising pendulum 45 pivotally mounted at 46 and a gear 47 provided with teeth 48 over a substantial portion of the circumference thereof but provided also with a toothless portion 49. The escapement pendulum 45 is adapted to engage with the teeth 48 of gear 47. The shaft 23 to which conducting arm 22 is fastened extends through casing 44 and is rotatable therein. Mounted upon the shaft 23 within the casing 44 is a gear 50 meshed with a pinion 51 fixedly mounted to gear 47. Upon blowing of fuse link 27, conducting arm 22 begins to rotate in a clockwise direction in response to the force of spring means 24 and, by virtue of the toothless portion 49 of gear 47, arm 22 may move at high speed without any retardation thereby providing a sort of flipping motion to rapidly separate the fuse link ends. As soon as the teeth 48 of gear 47 engage with the escapement pendulum 45, arm 22 begins to move at a retarded speed to provide the desired time delay. However, before arm 22 engages with switching member 37,

the toothless portion 49 of gear 47 again comes into play and arm 22 is permitted to move at high speed without being further impeded in its final downward motion firmly to engage switching member 31 and complete the circuit through second fuse link 36.

The operation of the reclosing circuit-interrupting device described above will be obvious in view of the detailed description included above and no further description will be included here.

As a result of the improvements hereinbefore described, a reclosing circuit-interrupting device is provided whereby refusing of the device may be accomplished without momentary arcing or momentary interruption of the circuit and a simple and efficient time-delay device is provided constructed so that high-speed separation of the parts of the blown fuse to insure circuit interruption is provided together with assurance that the circuit will be satisfactorily closed through the second fuse link after a predetermined time delay.

Although a preferred embodiment of the invention has been disclosed in complete detail so as to insure a complete understanding of the invention, it is contemplated that details of the disclosed structure are capable of modifications and that other applications and features of the invention may occur to those skilled in the art. Hence, it is intended in the appended claims to cover all such modifications and changes as fall within the true spirit and scope of my invention.

What I claim as new and desire to secure by Letters Patent of the United States:

1. In a reclosing circuit-interrupting device, the combination of an insulating supporting member, a pair of spaced line terminals fixedly mounted on said supporting member, a pair of conducting arms projecting outwardly from said supporting member each terminating in a fuse-link receiving means, each of said arms being connected to one of said line terminals, a first fuse link carried between said fuse-link receiving means, a third terminal adjacent to but spaced from one of said line terminals, a second fuse link electrically interconnecting said third terminal and one of said line terminals, a pivotally mounted switching member electrically connected to said third terminal, and means for causing the projecting arm connected to said one line terminal adjacent said third terminal to engage conductively with said pivotally mounted switching member upon blowing of said first fuse link to connect electrically said second fuse link between said line terminals, said pivotally mounted switching member being arranged so that replacement of said first fuse link without interrupting the circuit through said second fuse link until the current path through said first fuse link has been reestablished may be accomplished.

2. In a reclosing circuit-interrupting device, the combination of an insulating supporting member, a pair of spaced line terminals mounted on said member, a first fuse link electrically interconnecting said line terminals, a second fuse link adapted to be connected between said line terminals upon blowing of said first fuse link, a pivotally mounted current transfer member, movable means for electrically engaging said current transfer member for causing said second fuse link to be connected in the circuit between said line terminals after blowing of said first fuse link, said pivotally mounted current transfer member being arranged to follow said movable

means to permit replacement of said first fuse link without interrupting the circuit through said second fuse link and means for electrically separating said current transfer means from said movable member when the current path through said first fuse link has been reestablished.

3. In a reclosing circuit-interrupting device, the combination of an insulating supporting member, a pair of spaced line terminals mounted on said member, a first fuse link electrically interconnecting said line terminals, a second fuse link adapted to be connected between said line terminals upon blowing of said first fuse link, current transfer means for connecting said second fuse link in the circuit between said line terminals a predetermined time after the blowing of said first fuse link, and time-delay means for causing said current transfer means to move first at high speed, then at low speed to give the desired time delay and, subsequently, at high speed satisfactorily to complete the circuit through said second fuse link.

4. In a reclosing circuit-interrupting device, the combination of an insulating supporting member, a pair of spaced line terminals mounted on said member, a first fuse link electrically interconnecting said line terminals, a second fuse link adapted to be connected between said line terminals upon blowing of said first fuse link, current transfer means for connecting said second fuse link in the circuit between said line terminals a predetermined time after the blowing of said first fuse link, and time-delay means including an escapement mechanism for causing said current transfer means to move first at high speed, then at low speed to give the desired time delay, and, subsequently, at high speed satisfactorily to complete the circuit through said second fuse link.

5. In a reclosing circuit-interrupting device, the combination of an insulating supporting member, a pair of spaced line terminals mounted on said member, a first fuse link electrically interconnecting said line terminals, a second fuse link adapted to be connected between said line terminals upon blowing of said first fuse link current transfer means for connecting said second fuse link in the circuit between said line terminals a predetermined time after the blowing of said first fuse link, and time-delay means including an escapement mechanism comprising an escapement gear having a toothless portion for causing said current transfer means to move first at high speed, then at low speed to give the desired time delay, and, subsequently, at high speed satisfactorily to complete the circuit through said second fuse link.

6. In a reclosing circuit-interrupting device, the combination of an insulating supporting member, a pair of spaced line terminals fixedly mounted on said supporting member, a pair of conducting arms biased for relative separation projecting outwardly from said supporting member each terminating in a fuse link receiving means, each of said arms being electrically connected to one of said line terminals, a first fuse link carried between said fuse link receiving means, a third terminal adjacent to but spaced from one of said line terminals, a second fuse link electrically interconnecting said third terminal and the other of said line terminals, means including the projecting arm connected to said one line terminal adjacent said third terminal for connecting said second fuse link into the circuit between said line terminals

upon blowing of said first fuse link, and time-delay means for causing said projecting arm connected to said one line terminal adjacent said third terminal to move first at high speed, then at low speed to give the desired time delay, and, subsequently, at high speed satisfactorily to complete the circuit through said second fuse link.

7. In a reclosing circuit-interrupting device, the combination of an insulating supporting member, a pair of spaced line terminals fixedly mounted on said supporting member, a pair of conducting arms biased for relative separation projecting outwardly from said supporting member each terminating in a fuse link receiving means, each of said arms being electrically connected to one of said line terminals, a first fuse link carried between said fuse link receiving means, a third terminal adjacent to but spaced from one of said line terminals, a second fuse link electrically interconnecting said third terminal and the other of said line terminals, means including the projecting arm connected to said one line terminal adjacent said third terminal for connecting said second fuse link into the circuit between said line terminals upon blowing of said first fuse link, and time-delay means including an escapement mechanism for causing said projecting arm connected to said one line terminal adjacent said third terminal to move first at high speed, then at low speed to give the desired time delay, and, subsequently, at high speed satisfactorily to complete the circuit through said second fuse link.

8. In a reclosing circuit interrupting device, the combination of an insulating supporting member, a pair of spaced line terminals fixedly mounted on said supporting member, a pair of conducting arms projecting outwardly from said supporting member each terminating in a fuse link receiving means, each of said arms being connected to one of said line terminals, a first fuse link carried between said fuse link receiving means, a third terminal adjacent to but spaced from one of said line terminals, a second fuse link electrically interconnecting said third terminal and one of said line terminals, a pivotally mounted switching member electrically connected to said third terminal, means for causing the projecting arm connected to said one line terminal adjacent said third terminal to engage conductively with said pivotally mounted switching member upon blowing of said fuse link to connect electrically said second fuse link between said line terminals, said pivotally mounted switching member being arranged to follow said projecting arm when replacing said first fuse link, and means for electrically separating said switching member from said projecting arm whereby replacement of said first fuse link without interrupting the circuit through said second fuse link until the current path through said first fuse link has been reestablished may be accomplished.

SIDNEY R. SMITH, JR.
